UNITED STATES PATENT OFFICE.

JAMES POWERS, OF NEW YORK, N. Y.

APPARATUS AND METHOD FOR FORMULATING AND TRANSLATING CODES.

1,815,406.

Specification of Letters Patent.

Patented Sept. 9, 1919.

Application filed July 22, 1916. Serial No. 110,628.

To all whom it may concern:

Be it known that I, JAMES POWERS, a citizen of the United States, residing at New York, in the county of New York and State 5 of New York, have invented a certain new and useful Apparatus and Method for Formulating and Translating Codes, of which the following is a specification.

This invention has to do with an apparatus and method of formulating and translating codes, and which may be herein designated as an automatic code machine or apparatus and method of using the same, and which is more briefly designated as a code 10 formulator and translator, the object of the invention being to provide a method and apparatus for transmitting messages or correspondence in code language thereby to do away with the use of code books and other similar known code media, while at the same 15 time providing an improved code system impossible of deciphering without the key thereto.

A further object of the invention is the 20 provision of a code apparatus which may be used in connection with an ordinary typewriter both to formulate and also to translate or transcribe the code message.

A further object of the invention is the 25 provision of a code apparatus simple in construction and operation and by means of which innumerable codes can be formulated as required, so that if desired such codes may be changed from day to day.

A further object of the invention is the 30 provision of a code machine which, in connection with an ordinary typewriter of the sender and a similar typewriter of the receiver, can be used to formulate and translate any desired code message in the ordinary 35 manner in which a typewriter is manipulated and without liability of such message being deciphered by an unauthorized party.

At the present time it is the practice to 40 use various code books or code systems in the formulation and translation of code messages, this requiring of course that the sender and receiver shall have a similar code book, so that if either one of these books is stolen 45 the code can be easily deciphered by an unauthorized person. It is also the practice for governments as well as others to at times change the codes to prevent this possibility,

but obviously each agent of a government wherever located must have a similar code 55 book and must be advised of any changes that are made from time to time. Not only this, but to formulate and translate such a code message requires the tedious use of such a code book, whereas by the present improvement, by means of the ordinary typewriter a code can be immediately formulated and immediately translated without the necessity of a code book or anything else other than this machine and the necessary key for the setting of the machine, and which key in the present instance may consist of a couple of numbers readily memorized by the user and receiver, or which can be readily transmitted through some other medium, as by telegraph, 70 from that which transmits the message.

Therefore the present invention does away with all code systems and code books and the waste of valuable time in using the same, and by means of which innumerable codes or new 75 combinations of letters can be made and changed from day to day, so that by the use of one machine the sender may send different codes to many different agents without the possibility of any one except the recipient 80 being able to read any other message.

In the drawings accompanying and forming part of this specification Figure 1 is a side view of this code apparatus; Fig. 2 is a top view of a part of the machine; Fig. 3 is 85 a top view of what may be herein designated as the code formulator and translator; and Fig. 4 is a cross-sectional view taken in line 4-4 of Fig. 3.

Similar characters of reference indicate 90 corresponding parts in the different figures of the drawings.

This machine, in the preferred form thereof, consists of an ordinary typewriter 2 having the usual keyboard 3 and key-levers 4, and in the present instance this typewriter is preferably mounted upon a suitable supporting medium or base 5, which base or supporting medium has at one end, preferably in front of the typewriter keyboard, a supporting pedestal 6 provided with a spider 7 carrying a sleeve or bushing 8 and a raceway 9 for the support of the code formulator and translator, which comprises a rotary disk 10 carrying a series 100 of depressible character keys 11 arranged in

circular formation and the characters of which keys correspond with those of the keyboard of a typewriter. These keys are shown as spring-controlled plungers guided by the disk 10 adjacent to their upper ends and by a worm wheel disk 12 adjacent to their lower ends. The upper disk 10 is connected by suitable connecting means or bolts 13 with the worm wheel disk 12 whereby 5 they will turn together on the rotation of the worm wheel disk 12 by a suitable worm 14 adapted to be manipulated by a crank 15, the manipulation of which worm 14 may be controlled by a Yale lock formed as a 10 barrel of the worm 14, so that the crank 15 may have its end in the form of a key whereby the worm 14 can only be turned by the insertion of the proper crank. In view of the numerous combinations of such locks, as 15 the Yale and others which could be used, it will be obvious that the code formulator and translator may be effectively locked in this way against improper tampering therewith. This worm 14 is suitably supported in position by bearings 16 carried by a part of the pedestal. A casing or drum 17 is secured to the disk 10 and, together with the fixed part or band 24 hereinafter described, encloses the worm disk 12, the band 24 being 20 provided with an opening 18 to permit the meshing of the worm 14 with the worm teeth of the disk 12. The rotary drum formed by the worm disk 12 and top disk 10 and casing 17 has a shaft 19 secured thereto 25 axially thereof, and this shaft extends into and preferably through the sleeve 8, it being provided with a ball bearing raceway 20 at its lower end to facilitate the easy turning of the drum. The underside of the worm 30 disk or wheel 12 is likewise provided with a raceway 21 between which and the raceway 9 of the pedestal may be located suitable ball bearings 22, and by means of which the drum is supported on the pedestal. The 35 lower end of the shaft 19 may be provided with means for permitting the instrument to be sealed so that tampering with the instrument can be immediately detected, since it will be necessary to break the seal in order 40 to remove the disk.

Carried by the spider 7 are projections 23 having secured thereto a band 24 forming with the drum 17 hereinbefore referred to a complete inclosure for most of the parts 45 hereinbefore described. The drum 17 and the band 24 are provided on their outer faces with registering marks and what may be designated as key numbers, the drum carrying a circular series of numbers running say from 1 up to any desired number 50 corresponding with the number of characters on the typewriter, and which series of numbers is designated as 25, while the band 24 likewise carries a circular series of 55 numbers designated as 26, which may be the

same or a different series of numbers from those on the drum, and these two sets of numbers constitute the key number of the machine so that by rotating the drum through the medium of the crank any number upon 70 the drum may be brought in juxtaposition to any number upon the band, which band of course has a fixed position and is not rotated, so that as shown in Fig. 1 the numeral 1 may be brought opposite the numeral 11 75 and the numeral 2 opposite the numeral 12, and so on.

Connected with each key lever 4 of the typewriter by a suitable link or wire 27 is a similar series of key levers 28 the rear end of 80 each of which, as at 29, is pivotally supported in the supporting means and the front end of which is provided with an upturned portion 30 forming a circular series of upturned members each of which is in position 85 to be manipulated by any one of the keys 11 of the code formulator and translator as the same is rotated on its pedestal.

In the present instance the shift key and space bar of the typewriter are not connected with the code formulator and translator, but are manipulated in the usual way by the operator, the former to obtain either the capital or small letters and the latter to space the words in the usual manner. 90

In operation the operator, in order to send a code message, will turn the character disk into any desired position other than that in which the characters will be the same as those on the typewriter. In other 100 words, he will turn the disk so that the letter A of the apparatus will operate some other key lever than the letter A of the typewriter. For instance, if the operator desired to send the code word "POWERS" he would 105 set the disk so that the letter P would operate another lever of the typewriter than the lever marked P, that is to say, for example, he would set it so that the lever P when depressed on the character-carrying 110 disk would depress say the key lever A of the typewriter, and the lever O of the character-carrying disk would depress whatever letter corresponded therewith according to the setting of the disk, and so on, so that 115 while the operator was writing the word "POWERS" the typewriter would write some unintelligible word, which, however, would always be the same when the same key number was used. This word might be 120 "A?O,U9" provided that in Fig. 2 the disk was rotated say twenty-four letters to the right to have the letter "P" correspond with the letter "A" on the typewriter. It will be understood, of course, that the unintelligible 125 word just quoted would not necessarily be the word that is written with the ordinary typewriter, because these letters do not come in the order as arranged on all typewriters, but they simply serve as an example. 130

It will be understood from the foregoing that the sending and receiving disks are duplicates, so that if the sending disk is set with the key number combination 1—11 and 5 this writes on the typewriter a certain unintelligible word it of course follows that when the receiver sets his disk with the same key number combination and depresses the letters of this unintelligible word the word 10 "POWERS" is written on the typewriter.

At the time the operator sets his character-carrying disks 17 in the manner shown this will bring the key numbers on the outside of the drum into a certain relation with 15 the key numbers on the band 26, and in this case say for example that this is 1—11, so that in writing the word "POWERS" to form an unintelligible word such as that hereinbefore referred to the key number will be 20 1—11. Consequently the operator, if the recipient does not know the particular key number of his code messages, will simply telegraph to the recipient of the message the key number 1—11, and thereupon the 25 recipient of the message will set his machine so that the character-carrying disk will have the numeral 1 in register with the numeral 11 on the band 26, whereupon when he depresses the plungers carrying the characters 30 of the unintelligible code word, as for instance "A?O,U9", the typewriting machine will write the word "POWERS".

Thus it will be observed that by the use of this code formulator and translator the 35 sender and recipient, each having a similar typewriter and one of these code machines, can formulate and translate any desired code message, changing the same daily if necessary by merely transmitting a different key 40 number, without the use of code books or other similar media, and that by rotating the disk any desired combination of letters may be obtained limited only by the combinations of letters, numerals and other characters on the 45 typewriter, for obviously the letter A on the code machine, instead of writing the letter P on the typewriter, might write the interrogation point, or the period, or a numeral. It thus follows that one agent of a government 50 for instance would not be able to decipher any other agent's message, as each agent could have a different key number, so that several agents could send different messages to their government and neither could 55 read the other's message, while the United States Government for instance could decipher all of the messages, although formed on the same kind of machines and the same kind of typewriters, so that although 60 thousands of people may have similar code or master machines and similar typewriters no one of them could read the message of any other unless he had the proper key number.

Furthermore, it will be observed that the 65 necessity of changing the ordinary book

code or devising further codes is entirely unnecessary, since with a master code machine of the kind described the owner thereof may have as many combinations of letters and characters or codes as the various arrangements of the letters on the typewriter will permit, which are almost innumerable, and that in addition to this by means of the improved key crank the manipulation of the machine is also prevented and detection insured by reason of the sealing means used in case the machine is manipulated improperly. It therefore follows that even though the message should be stolen in transit, and even though the person stealing it should 70 have one of these code machines, he still would be unable to decipher the code message unless he had the key number, which would only be within the memory of the recipient or, as hereinbefore stated, could be 75 sent by a separate mode of transmission. In other words, without the proper key number the machine is useless to decipher any message that may be written thereon, and as this key number may be carried in the memory 80 of the users of the machine it therefore cannot be ascertained as is the case where it is carried in a book or some other written memorandum, in other words it cannot be stolen. It will also be obvious that 85 the sender of the message may have one key number for the recipient, who in answering the message may use an entirely different key number previously arranged between the parties or transmitted in some way other 90 than with the message if this is undesirable.

Thus it will be observed, in conclusion, that by a very simple and inexpensive mechanism and the use of ordinary typewriters I have provided an improved system of 95 formulating and translating codes capable of being changed from day to day as occasion requires and by means of which different users may send different messages without one being able to decipher that of 100 another, although using the same identical machine.

In addition to the advantages hereinbefore described a machine of this kind is readily adapted for use in connection with foreign correspondence where it is desired to send a letter for instance in the Russian language more or less unintelligible to any one familiar with that language. For instance, if an operator desires to send a letter in the Russian language to some one in Russia it would be merely necessary to have the typewriter provided with Russian characters while the code machine will have its keys provided with English characters. Consequently on 115 the depression of the English characters of the code machine the letter will be written by the typewriter in Russian type, so that when received by the foreign correspondent in Russia the clerk, who would probably 120

125

be familiar with the Russian characters but not necessarily with the English language, would merely have to depress the keys of the code machine, which in this case would 5 have Russian characters thereon, whereupon the typewriter, which of course would be provided with English type, would re-form the letter into an English one for the benefit of the recipient, and this would be more or 10 less unintelligible to the clerk, since he not being familiar with the English language could not read it and as the letter having been originally written in the English manner would be more or less unintelligible because the Russian characters would be considerably jumbled up, the words not being 15 in their proper places, etc.

I claim as my invention:

1. The combination with a typewriter, of 20 a code machine located away from the finger keys of and to one side of the typewriter and having a series of characters corresponding with those of the typewriter and shiftable as a whole into different positions relatively to the characters of the typewriter, thereby to 25 permit the formulation of many thousands of different codes, and means for actuating the characters of the typewriter on the manipulation of the characters of the code machine.
2. The combination with a typewriter, of 30 a code machine having a circular series of characters corresponding with those of the typewriter and shiftable into different positions relatively to the characters of the typewriter, and means for actuating the characters of the typewriter on the manipulation 35 of the characters of the code machine.
3. The combination with a typewriter, of 40 a code machine located away from the finger keys of and in front of the typewriter and having a series of characters corresponding with those of the typewriter and shiftable into different positions relatively to the characters of the typewriter, means for actuating the characters of the typewriter on the manipulation 45 of the characters of the code machine, and means for shifting the characters of the code machine.
4. The combination with a typewriter, of 50 a code machine having a series of characters corresponding with those of the typewriter and shiftable into different positions relatively to the characters of the typewriter, means for actuating the characters of the typewriter on the manipulation of the characters of the code machine, and means for shifting the characters of the code machine and comprising a worm wheel and a worm.
5. The combination with a typewriter, of 55 a code machine having a series of characters corresponding with those of the typewriter and shiftable into different positions relatively to the characters of the typewriter, and means for actuating the characters of the typewriter on the manipulation 60 of the characters of the code machine, and means for shifting the characters of the code machine and including a key having a crank.

typewriter on the manipulation of the characters of the code machine, means for shifting the characters of the code machine, and means for locking the shifting means.

6. The combination with a typewriter, of 70 a code machine having a series of characters corresponding with those of the typewriter and shiftable into different positions relatively to the characters of the typewriter, means for actuating the characters of the typewriter on the manipulation of the characters of the code machine, means for shifting the characters of the code machine, and means for locking the shifting means and including a key having a crank.

7. The combination with a typewriter, of 80 a code machine having a series of characters corresponding with those of the typewriter and shiftable into different positions relatively to the characters of the typewriter, 85 means for actuating the characters of the typewriter on the manipulation of the characters of the code machine, means for shifting the characters of the code machine and comprising a worm wheel and a worm, and 90 means for locking the worm wheel and worm against movement.

8. The combination with a typewriter, of 95 a code machine having a circular series of characters corresponding with those of the typewriter and shiftable into different positions relatively to the characters of the typewriter, means for actuating the characters of the typewriter on the manipulation of the characters of the code machine, and means 100 for rotatively shifting the characters of the code machine.

9. The combination with a typewriter, of 105 a code machine having a circular series of characters corresponding with those of the typewriter and shiftable into different positions relatively to the characters of the typewriter, means for actuating the characters of the typewriter on the manipulation of the characters of the code machine, means for 110 rotatively shifting the characters of the code machine, and means for locking said shifting means.

10. The combination with a typewriter, of 115 a code machine having a circular series of characters corresponding with those of the typewriter and shiftable into different positions relatively to the characters of the typewriter, means for actuating the characters of the typewriter on the manipulation of the characters of the code machine, means for 120 rotatively shifting the characters of the code machine and comprising a worm wheel and a worm, and means for locking said worm and worm wheel and including a crank-formed key also operative to rotate the worm.

11. The combination with a typewriter, of 125 a code machine having a series of characters corresponding with those of the typewriter 130

- and shiftable into different positions relatively to the characters of the typewriter, and means for actuating the characters of the typewriter on the manipulation of the 5 characters of the code machine, said code machine having sets of key characters, one set for each character of the series, by means of which the setting of the code machine is determined.
- 10 12. The combination with a typewriter, of a code machine having a circular series of characters corresponding with those of the typewriter and shiftable into different positions relatively to the characters of the typewriter, and means for actuating the characters of the typewriter on the manipulation of the characters of the code machine, said code machine having key characters by means of which the setting of the code machine is determined.
- 15 13. The combination with a typewriter, of a code machine having a shiftable series of movable characters corresponding with those of the typewriter and shiftable as a whole 20 into substantially as many different positions as there are characters of said shiftable series without eliminating the use of any of the corresponding characters on the typewriter, and means connecting each of said 25 characters with a character of the typewriter thereby to manipulate the characters of the typewriter.
- 20 14. The combination with a typewriter, of a code machine having a rotary series of 35 movable characters corresponding with those of the typewriter, and means connecting each of said characters with a character of the typewriter thereby to manipulate the characters of the typewriter.
- 30 15. The combination with a typewriter, of a code machine having a shiftable series of movable characters corresponding with those of the typewriter, and means connecting each of said characters with a character of the typewriter thereby to manipulate the characters of the typewriter.
- 35 16. The combination with a typewriter, of a code machine located away from the finger 40 keys of and to one side of the typewriter and comprising a shiftable member carrying a series of shiftable characters connected with and corresponding to the characters of the typewriter and operative to actuate the characters of the typewriter on the manipulation of the characters of the code machine.
- 45 17. The combination with a typewriter, of a code machine comprising a shiftable member carrying a series of shiftable characters 50 corresponding to the characters of the typewriter and operative to actuate the characters of the typewriter on the manipulation of the characters of the code machine, said code machine having a series of sets of key characters thereon, one set for each character of the series, whereby on the setting of the key characters in a predetermined way the typewriter can be manipulated to form a code or to translate it.
- 55 18. The combination with a typewriter, of a code machine comprising a rotatable disk, a series of movable character carrying devices carried by the disk for rotation thereby, and a series of levers connected with the character levers of the typewriter and each 60 operative by any one of the character carrying devices of the rotatable disk.
- 65 19. The combination with a typewriter, of a code machine comprising a rotatable disk, a series of movable character carrying devices carried by the disk for rotation thereby, a series of levers connected with the character levers of the typewriter and each 70 operative by any one of the character carrying devices of the rotatable disk, and means for rotating the disk.
- 75 20. The combination with a typewriter, of a code machine comprising a rotatable disk, a series of movable character carrying devices carried by the disk for rotation thereby, a series of levers connected with the character levers of the typewriter and each 80 operative by any one of the character carrying devices of the rotatable disk, and means for rotating the disk and comprising a worm 85 and a worm wheel the latter connected with the disk for rotation therewith.
- 85 21. The combination with a typewriter, of a code machine comprising a rotatable disk, a series of movable character carrying devices carried by the disk for rotation thereby, a series of levers connected with the character levers of the typewriter and each 90 operative by any one of the character carrying devices of the rotatable disk, means for rotating the disk and comprising a worm 95 and a worm wheel the latter connected with the disk for rotation therewith, and a lock for the disk for rotation therewith.
- 95 22. The combination with a typewriter, of a code machine comprising a rotatable disk, a series of movable character carrying devices carried by the disk for rotation thereby, a series of levers connected with the character levers of the typewriter and each 100 operative by any one of the character carrying devices of the rotatable disk, means for rotating the disk and comprising a worm 105 and a worm wheel the latter connected with the disk for rotation therewith, and a lock for locking the worm wheel against rotation.
- 105 23. The combination with a typewriter, of a code machine comprising a rotatable disk, a series of movable character carrying devices carried by the disk for rotation thereby, a series of levers connected with the character levers of the typewriter and each 110 operative by any one of the character carrying devices of the rotatable disk, means for rotating the disk and comprising a worm 115 and a worm wheel the latter connected with the disk for rotation therewith, and a lock for locking the worm wheel against rotation and comprising a crank-formed key.
- 115 24. The combination with a typewriter, of a code machine comprising a rotatable disk, a series of movable character carrying devices carried by the disk for rotation thereby, a series of levers connected with the character levers of the typewriter and each 120 operative by any one of the character carrying devices of the rotatable disk, means for rotating the disk and comprising a worm 125 and a worm wheel the latter connected with the disk for rotation therewith, and a lock for locking the worm wheel against rotation and comprising a crank-formed key.
- 125 25. The combination with a typewriter, of a code machine comprising a rotatable disk, a series of movable character carrying de- 130

5 vices carried by the disk for rotation thereby, a series of levers connected with the character levers of the typewriter and each operative by any one of the character carrying devices of the rotatable disk, means for rotating the disk and comprising a worm and a worm wheel the latter connected with the disk for rotation therewith, a lock for locking the worm wheel against rotation and 10 comprising a crank-formed key, means for supporting the disk and worm wheel, and a seal for preventing the withdrawal of the disk and its worm from the worm wheel.

15 24. The combination with a typewriter having a series of type-actuating key levers, of a supporting base therefor, a rotary drum mounted on said base and comprising a disk and a worm wheel connected for rotation, a series of depressible character carrying keys 20 corresponding in number with the characters of the typewriter, a series of levers connected one with each of the key levers of the typewriter and having a part thereof in position to be operated by any one of the character carrying keys of the drum, and 25 means for rotating said worm wheel.

25 26. The combination with a typewriter having a series of type-actuating key levers, of a supporting base therefor, a rotary drum mounted on said base and comprising a disk and a worm wheel connected for rotation, a series of depressible character carrying keys corresponding in number and arrangement with the characters of the typewriter, 30 a series of levers connected one with each of the key levers of the typewriter and having a part thereof in position to be operated by any one of the character carrying keys of the drum, a worm for rotating said worm 35 wheel, and means for rotating said worm.

40 26. The combination with a typewriter having a series of type-actuating key levers, of a supporting base therefor, a rotary drum mounted on said base and comprising a disk and a worm wheel connected for rotation, a series of depressible character carrying keys corresponding in number with the characters of the typewriter, a series of levers connected one with each of the key levers 45 of the typewriter and having a part thereof in position to be operated by any one of the character carrying keys of the drum, a worm for rotating said worm wheel, and means for rotating said worm, said means 50 comprising a key and a lock formed as a part of said worm for manipulation by the key.

55 27. The combination with a typewriter having a series of key levers, of a supporting base therefor having a pedestal, a rotary drum mounted thereon and having a shaft projecting into said pedestal and comprising a disk and a worm wheel secured for rotation, said worm wheel and pedestal having a ball bearing raceway, a series of 60

70 spring-controlled key plungers carried by the disk and worm wheel, a series of levers corresponding with the number of typewriter key levers and connected therewith and in position to be actuated by the spring-controlled plungers, a worm carried by said drum and in mesh with the worm wheel, and means for locking the worm and for actuating it thereby to rotate the drum and its key levers. 75

80 28. The combination with a typewriter having a series of key levers, of a supporting base therefor having a pedestal, a rotary drum mounted thereon and having a shaft projecting into said pedestal and comprising a disk and a worm wheel secured for rotation, said worm wheel and pedestal having a ball bearing raceway, a series of 85 spring-controlled key plungers carried by the disk and worm wheel, a series of levers corresponding with the number of typewriter key levers and connected therewith and in position to be actuated by the spring-controlled plungers, a worm carried by said drum and in mesh with the worm wheel, 90 means for locking the worm and for actuating it thereby to rotate the drum and its key levers, and means for sealing the drum thereby to prevent the removal thereof from its pedestal. 95

100 29. The combination with a typewriter having a series of key levers, of a supporting base therefor having a pedestal, a rotary drum mounted thereon and having a shaft projecting into said pedestal and comprising a disk and a worm wheel secured for rotation, said worm wheel and pedestal having a ball bearing raceway, a series of 105 spring-controlled key plungers carried by the disk and worm wheel, a series of levers corresponding with the number of typewriter key levers and connected therewith and in position to be actuated by the spring-controlled plungers, a worm carried by said drum and in mesh with the worm wheel, 110 and means for locking the worm and for actuating it thereby to rotate the drum and its key levers, said drum and pedestal having a series of key characters thereon. 115

120 30. The combination with a typewriter having a series of key levers, of a supporting base therefor having a pedestal, a rotary drum mounted thereon and having a shaft projecting into said pedestal and comprising a disk and a worm wheel secured for rotation, said worm wheel and pedestal having a ball bearing raceway, a series of 125 spring-controlled key plungers carried by the disk and worm wheel, a series of levers corresponding with the number of typewriter key levers and connected therewith and in position to be actuated by the spring-controlled plungers, a worm carried by said drum and in mesh with the worm wheel, means for locking the worm and for actuati- 130

ing it thereby to rotate the drum and its key levers, and means for sealing the drum thereby to prevent the removal thereof from its pedestal, said drum and pedestal having 5 a series of key characters thereon.

31. The combination with a typewriter having a series of type-actuating key levers, of a supporting base therefor, a rotary drum mounted on said base and comprising a disk 10 and a worm wheel connected for rotation, a series of depressible character-carrying keys corresponding in number with the characters of the typewriter, and a series of levers connected one with each of the key 15 levers of the typewriter and having a part thereof in position to be operated by any one of the character carrying keys of the drum, the drum and supporting base having thereon a series of key characters whereby 20 on the setting of the key characters in a predetermined way the typewriter may be manipulated to form a code or to translate it.

32. The combination with a typewriter, of a code machine comprising a rotatable 25 disk, a series of movable character-carrying devices carried by the disk for rotation thereby, and a series of levers connected with the character levers of the typewriter and each operative by any one of the character-carrying devices of the rotatable disk, said code machine having a series of sets of 30 key characters thereon, one character of each set being rotatable with the disk and the other of each set fixed with relation to the disk whereby on the setting of the key characters in a predetermined way the typewriter may be manipulated to form a code or to translate it.

33. The combination with a typewriter, 40 of a code machine comprising a shiftable member carrying a series of shiftable characters corresponding in number and arrangement with the characters of the typewriter, means for actuating the characters 45 of the typewriter on the manipulation of the shiftable characters of the shiftable member, said code machine having a series of key characters corresponding in number with the number of shiftable characters of 50 the code machine, said series comprising a shiftable series and a fixed series, the former shiftable with the shiftable member.

34. The combination with a typewriter, of a code machine located away from the 55 finger keys of and to one side of the typewriter and having a series of characters corresponding with those of the typewriter and shiftable into different positions relatively to the characters of the typewriter, 60 means for actuating the characters of the typewriter on the manipulation of the characters of the code machine, and means for locking the code machine.

35. The combination with a typewriter, 65 of a code machine having a circular series

of characters corresponding with those of the typewriter and rotatable into different positions relatively to the characters of the typewriter, means for actuating the characters of the typewriter on the manipulation of the characters of the code machine, and means for locking said code machine. 70

36. The combination with a typewriter, of a code machine having a series of characters corresponding with those of the typewriter and shiftable into different positions relatively to the characters of the typewriter, means for actuating the characters of the typewriter on the manipulation of the characters of the code machine, and means for locking the code machine, said code machine having a series of key characters, said series comprising a shiftable series and a fixed series, the former shiftable with the shiftable characters. 75 80 85

37. The combination with a typewriter, of a code machine having a circular series of characters corresponding with those of the typewriter and rotatable into different positions relatively to the characters of the typewriter, means for actuating the characters of the typewriter on the manipulation of the characters of the code machine, and means for locking said code machine, said code machine having a series of key characters, said series comprising a shiftable series and a fixed series the former shiftable with the rotatable characters. 90 95

38. A code writing machine comprising two sets of movable characters, one set shiftable as a whole relatively to the other into as many different positions as there are characters in a set, whereby said shiftable set may be shifted so that the operation of any of the movable characters thereof will operate the movable characters of the other set without eliminating the use of any of the corresponding characters of such other set, and means for actuating the characters of one set on the movement of the 100 characters of the other. 105 110

39. A code writing machine comprising two sets of movable characters, one set rotatable relatively to the other whereby said rotatable set may be rotated so that the operation of any of the movable characters thereof will operate any of the movable characters of the other set, and means for actuating the characters of one set on the movement of the characters of the other. 115 120

40. A code writing machine comprising two sets of duplicate movable characters, one set shiftable as a whole relatively to the other into as many different positions as there are characters in a set, whereby said shiftable set may be shifted so that the operation of any of the movable characters thereof will operate the movable characters of the other set without eliminating any of the corresponding characters of such other 125 130

set, and means for actuating the characters of one set on the movement of the characters of the other.

41. A code writing machine comprising two sets of movable characters, one set shiftable relatively to the other whereby said shiftable set may be shifted so that the operation of any of the movable characters thereof will operate any of the movable characters of the other set, and means for actuating the characters of one set on the movement of the characters of the other, said machine having two series of combination symbols one series fixed and the other shiftable relatively to the fixed series.

42. A code writing machine comprising two sets of movable characters, one set rotatable relatively to the other whereby said rotatable set may be rotated so that the operation of any of the movable characters thereof will operate any of the movable characters of the other set, and means for actuating the characters of one set on the movement of the characters of the other, said machine having two series of combination symbols one series rotatable with said set of rotatable characters relatively to the other series of symbols.

43. A code writing machine comprising two sets of duplicate movable characters, one set shiftable relatively to the other whereby said shiftable set may be shifted so that the operation of any of the movable characters thereof will operate any of the movable characters of the other set, and means for actuating the characters of one set on the movement of the characters of the other, said machine having two series of combination symbols one series shiftable with said set of shiftable characters and relatively to the other series of symbols.

44. A code writing machine comprising two sets of movable characters, one set shiftable relatively to the other whereby said shiftable set may be shifted so that the operation of any of the movable characters thereof will operate any of the movable characters of the other set, means for actuating the characters of one set on the movement of the characters of the other, and two series of combination symbols one series shiftable relatively to the other and with the shiftable characters.

45. A code writing machine comprising two sets of duplicate movable characters, one set rotatable relatively to the other, and means for actuating the characters of one set on the movement of the characters of the rotatable set, said machine having two series of combination symbols corresponding in number with the number of characters of the rotatable set and one series rotatable relatively to the other series of symbols and with the rotatable set of characters whereby on the setting of the symbols in a predetermined

manner a code may be formulated or translated.

46. A code writing machine comprising two sets of duplicate movable characters, one set rotatable relatively to the other, means for actuating the characters of one set on the movement of the characters of the rotatable set, said machine having two series of combination symbols corresponding in number with the number of characters of the rotatable set and one series rotatable relatively to the other series of symbols and with the rotatable set of characters whereby on the setting of the symbols in a predetermined manner a code may be formulated or translated, and means for rotating the rotatable set of characters whereby the operation of any one of the characters thereof will operate any one of the characters of the other set.

47. A code writing machine comprising two sets of duplicate movable characters, one set rotatable relatively to the other, means for actuating the characters of one set on the movement of the characters of the rotatable set, said machine having two series of combination symbols corresponding in number with the number of characters of the rotatable set and one series rotatable relatively to the other series of symbols and with the rotatable set of characters whereby on the setting of the symbols in a predetermined manner a code may be formulated or translated, and means for locking the rotatable set of characters against movement.

48. A code writing machine comprising two sets of duplicate movable characters, one set rotatable relatively to the other, means for actuating the characters of one set on the movement of the characters of the rotatable set, said machine having two series of combination symbols corresponding in number with the number of characters of the rotatable set and one series rotatable relatively to the other series of symbols and with the rotatable set of characters whereby on the setting of the symbols in a predetermined manner a code may be formulated or translated, means for rotating the rotatable set of characters whereby the operation of any one of the characters thereof will operate any one of the characters of the other set, and means for locking the means for rotating the rotatable set of characters.

49. A code writing machine comprising two sets of movable characters, one positioned to impart impressions and each having finger keys, said two sets of characters having a duplicate arrangement and one set rotatable relatively to the other, and means for actuating the impression set of characters on the movement of the finger keys of the other set.

50. A code writing machine comprising two sets of movable characters, said two sets of characters having a duplicate arrange-

ment and one set rotatable relatively to the other, and means for actuating the characters of one set on the movement of the characters of the other set, said machine having 5 two series of combination symbols, one series rotatable relatively to the other and with the rotatable set of characters whereby on the setting of the symbols in a predetermined manner a code may be formulated or translated.

51. A code writing machine comprising a supporting member, a typewriter and a rotatable member carried by said supporting member, a set of character-carrying keys 15 carried by said rotatable member and corresponding in number and arrangement with the character keys of the typewriter, means for actuating the typewriter keys on the manipulation of the keys of the rotatable 20 member, and two series of combination symbols, one series carried by the supporting member and the other by the rotatable member whereby on the setting of the symbols in a predetermined manner by the rotation of 25 the rotatable member a code may be formulated or translated.

52. In a machine of the class described, the combination of a typewriter and a code forming machine connected therewith, said 30 code machine having a shiftable character carrying medium constructed and organized so that upon changing as a whole the position of said shiftable character-carrying medium, so that its characters will be in a 35 different arrangement from those of the typewriter with which it is connected the manipulation of any of the characters of the character-carrying medium will operate any of the characters of the typewriter 40 thereby to permit the formulation of many

thousands of different codes, or the translation of any of such codes on the typewriter and means operatively connecting the keys of the typewriter with the characters of the code forming machine.

53. In a machine of the class described, the combination of a typewriter and a code forming machine connected therewith, said code machine having a shiftable character carrying medium constructed and organized 45 so that upon changing as a whole the position of said shiftable character-carrying medium, so that its characters will be in a different arrangement from those of the typewriter with which it is connected, the 50 position of said shiftable character-carrying medium varying according to the number of the characters carried thereby and without eliminating the use of any of the corresponding characters on the typewriter 55 the manipulation of any of the characters of the character-carrying medium will operate any of the characters of the typewriter thereby to permit the formulation of many thousands of different codes or to translate 60 any of such codes on the typewriter, and means operatively connecting the keys of the typewriter with the characters of the code forming machine, said shiftable character-carrying medium carrying one series 65 of combination symbols shiftable relatively to another series of symbols thereby to form a series of sets of combination keys corresponding with the number characters carried by said shiftable character-carrying medium for the proper setting of said shiftable 70 75 medium.

Signed at 1822 Park Row Building, New York, N. Y., this 21st day of July, 1916.

JAMES POWERS.
